UNITED STATES PATENT OFFICE.

JOHN EDWARD THORNTON, OF LONDON, ENGLAND.

CINEMATOGRAPH FILM MATERIAL.

Original application filed December 13, 1923, Serial No. 680,511, and in Great Britain December 27, 1922.
Divided and this application filed June 8, 1925. Serial No. 35,761.

This invention relates to reinforced film material of double-standard width and half-standard thickness for the production of two-color positive cinematograph films such 5 as described in my concurrent application Serial No. 35,760 filed 8th June, 1925.

That specification described the production of cinematograph two-color positive film-prints of the type in which one of the 10 color prints is formed upon one section-film of half the standard thickness and the other color-printed upon another section-film of half the standard thickness and in which the coloring matter is incorporated in the sensitized colloid, the two section-prints being 15 afterwards joined together to produce a single film of full standard thickness.

The standard film material commonly used 20 for producing monochrome pictures, sensitized upon one side only, and also the duplex film material, sensitized upon both sides, for use in producing two-color pictures, are made of an approximate thickness of .00600 inch; and film material of such thickness 25 is strong enough to successfully withstand the usual rough handling in the film printery.

The film material, for producing two-color films, of half standard thickness is made of 30 an approximate thickness .00300 inch and is not of sufficient strength to successfully withstand the handling during the successive processes in the film printery without considerable waste and loss arising from 35 breakage.

In my Patent 1,229,546, dated 12th June, 1917, I described a film material of half standard thickness (.00300 inch) provided with a temporary reinforcement or stripping 40 back of smooth glossy paper heavily coated, waterproofed and polished, so prepared that the film will remain attached thereto during the printing, developing and washing operations but be readily detached when required, 45 the film being built up thereon with a succession of layers comprising a layer of celluloid or cellulose acetate nearly .00300 inch thick, a sensitive colloid layer .00100 inch thick superimposed thereon, and an adhesive sub- 50 stratum placed between the two to ensure their permanent adhesion so that the three layers form one homogeneous strip of film material. I also described this thin reinforced film material as made of double width 55 to enable the complementary section images

being printed thereon side-by-side to face the same way, and after slitting the double-width film the two films were cemented with the colloid face of the lower one to the glossy celluloid back of the upper one. In practice 60 this proved uncertain owing to the difficulty of making a perfectly satisfactory and permanently secure union between the two materials of totally different physical character 65 with the result that the glossy celluloid face and the colloid face came apart after the shortest use.

In practice it was eventually found that the reinforcement or backing of a smooth glossy or polished paper did not adhere to 70 the celluloid film sufficiently firmly during the various processes in the film printery, and it often became detached and completely spoiled before the final stage of cementing 75 the films together was reached.

Another fault in that invention was that when images of the relief type were required (which need to be printed from the back through the celluloid but developed from the front) the reinforcing strip could not be used at all, because it was attached only to the back of the celluloid; therefore the use of such reinforcement was restricted to the production only of images that are both printed and developed from the front 80 and must therefore be of the flat (non-relief) type.

In my application No. 608,511, filed 13th December, 1923, some of the difficulties are overcome, firstly by making one of the film- 90 prints with its image-series reversed in relation to the other complementary film-print, and secondly by cementing the two film-prints face-to-face, so that both the faces cemented are of the same colloid material 95 with the same physical characteristics, the images being inside.

The object of this invention is to produce an improved ready colored sensitized film material of double standard width and half standard thickness provided with a temporary reinforcement of paper forming an integral part thereof for use in the production of two-color cinematograph films of standard width and thickness.

According to the present invention in the temporary reinforcement or backing, I abolish the glossy or polished face and prepare or select therefor a paper provided with multitudinous fine teeth or grain to which 110

an adhesive coating such as rubber solution or gelatine will by the process of shrinkage become interlocked and firmly shrunk upon every single tooth in the manner hereinafter more particularly described.

Referring to the accompanying drawings:

Fig. 1 is a sectional view of ready-colored sensitized film material with reinforcement 10 A of paper applied to the transparent base support B adapted for exposing through the colloid face D for making non-relief prints.

Fig. 2 is a sectional view of ready-colored sensitized film-material with reinforcement 15 A¹ of paper applied to the sensitized colored colloid D adapted for exposure through the base-support B for making relief prints.

Fig. 3 is a view of film-material showing 20 stripes of colored colloid with paper reinforcement on back.

Fig. 4 is a view of same perforated.

Fig. 5 is a view of film-material showing 25 stripes of colored colloid with paper reinforcement on face.

Fig. 6 is a view of same perforated.

Fig. 7 is a view of sheet of film-material 30 with a plurality of stripes of colored colloid alternately orange-red and blue-green adapted to be cut into strips of material of double standard width with two parallel colored stripes.

Fig. 8 is a view of a modified sheet of film-material with a plurality of stripes of 35 colored colloid alternately orange-red and blue-green adapted to be cut into strips of material of double standard width with two parallel colored stripes.

The paper reinforcement A or A¹ is of 40 double standard width with indentations or fine teeth over the surface and upon this rough surface is coated an adhesive layer C of rubber solution or gelatine which will flow into all the interstices on the surface and on drying 45 will adhere firmly thereto.

This paper reinforcement A, A¹ provides 50 a continuous flexible non-polished support and serves the double-purpose of a smooth casting surface upon which to form the film and of a temporary support to which the film firmly adheres with absolute certainty throughout all the printing, developing, washing, and drying operations, but permits reasonably easy detachment when required.

For printing and developing from the front to give flat non-relief images the sensitive film material is constructed by coating 55 upon the adhesive layer C of rubber solution a layer of transparent base-support B such as celluloid, a layer of adhesive substratum b, and a layer of sensitive colored colloid D in two parallel differently colored stripes.

For printing through the back and developing from the front to give images in 60 relief the paper reinforcement A¹ is attached

to the sensitive colloid D the sensitive film material being constructed by coating upon the adhesive layer C of rubber or gelatine, a layer of sensitized colored colloid D in two parallel differently colored stripes, a layer of adhesive substratum b and a layer of transparent base-support such as celluloid.

For printing non-relief images the reinforcing paper which is attached to the celluloid back of the film material may remain attached thereto until the two films are cemented together image-face to image-face. Or may remain attached until after the final development and then be stripped off immediately before the two films are cemented together celluloid-back to celluloid-back.

For printing raised or relief images the reinforcing paper which is attached to the sensitive front of the film material may remain attached thereto until after final development and be stripped off immediately before the two films are cemented together image-face to image-face. Or may remain attached until the two films are cemented together celluloid-back to celluloid-back.

The complete section film material therefore comprises three main layers, one of transparent celluloid (or similar waterproof material) to constitute the film base-support, another of sensitized ready-colored colloid material in or upon which the print itself is made and another of paper with fine teeth or grain on the surface filled with an adhesive, which serves only for temporarily strengthening and reinforcing the otherwise too thin film, to these three main layers being added a substratum layer of the usual type placed between the celluloid and the colloid layers in order to effect an indissoluble union of the two.

In the manufacture of the thin reinforced film material the reinforcing paper or backing is cut to double standard film width; upon the surface which is grained or toothed an adhesive of rubber or gelatine is flowed or spread into the hollows or spaces between the teeth or grain and a coating or successive coatings of the desired thickness of celluloid and sensitive colored colloid are applied. For flat or non-relief pictures the celluloid 115 is first coated and for raised or relief pictures the colloid is first coated.

Each of these layers is applied by means of the same or similar coating and spreading machinery combined with heating and cooling devices as are generally used in manufacturing sensitized papers; and the drying of these coatings is effected by passing the coated web through the usual paper-drying rooms supplied with dust-filtered, heated and dried air by means of the usual pressure and exhaust fans.

This toothed surface is first prepared by coating with a thin layer of pure para rubber dissolved in benzole, benzene or other 130

suitable solvent of rubber, which is then dried. It is preferred to then apply a second coating of the rubber solution, which is also dried. The first or both of these coatings 5 will flow into the hollows or valleys between the points or hills formed by the grain, until they are filled up and a perfectly smooth level surface is produced.

To this rubber-covered smooth surface is 10 next applied the layer of transparent film base, either by one or more coatings.

The substratum solution is next applied to the celluloid layer, when the substratum is dry the sensitized colored colloid layer 15 is applied in stripes by flowing or by passing around a roll which dips into a trough of solution, and when this layer is finally dry the film manufacture is finished.

The web is next slit into narrow strips of 20 double the requisite width of the cinematograph film, and the strips are next perforated to suit the printing and other machines by which the prints are produced.

In manufacturing the thin film material 25 with its reinforcement at the front transparent celluloid at the back, and sensitive colored colloid in the centre, for producing prints with relief-images, the order for applying the coatings is varied as follows:—

30 The toothed surface of the paper is first prepared by coating it with a very thin isolating layer of gelatine containing glycerine, molasses or sugar, applied as a thin solution, and if necessary a second coat can be 35 applied. The gelatine will flow into the hollows and fill up the grain of the rough paper to produce a smooth surface as in the example of rubber layer already described.

To this smooth gelatine-coated surface is 40 next applied the layer of sensitized colored colloid as in the previous example.

The substratum layer is next applied in the manner already described.

Finally the transparent celluloid base layer 45 is applied and when dry the film is complete.

In producing film material such as hereinbefore described it is made with two differently colored stripes one containing orange-red coloring matter and the other 50 containing blue-green coloring matter, to give ready colored-pictures directly by development.

In manufacturing a wide web of paper is coated in the manner hereinbefore described, 55 the sensitive colored colloid being applied in a series of alternating stripes of orange-red and blue-green (or it may be red and blue) each extending longitudinally of the web, and when slit into double-width strips each 60 strip comprises the two sets of complementary colors (orange-red and blue-green or red and blue) required to produce a series of complete two-color pictures.

The essence of success in manufacture of 65 such reinforced film is the use of a paper

having a pronounced tooth or grain and an adhesive filling which adheres to and becomes firmly interlocked with each one of such teeth, but has a perfectly smooth top surface and which is at the same time sufficiently adhesive to hold the superimposed film layer with absolute security during all the subsequent processes of manipulation, but also is capable of permitting a complete and perfect release of the superimposed film 70 layer from the reinforcing paper layer when the film-print is finished.

The function of the first adhesive layer is to secure a perfect grip upon all the teeth 75 of the grainy paper surface, which is effected by the process of shrinking during drying; and the function of the second adhesive layer is to produce a perfectly smooth surface upon the upper side and a perfect union with the first adhesive layer upon the 80 lower side; and the function of this smooth upper surface is to enable the superimposed film layer to come away from the adhesive layer as a perfectly clear transparency, whereas if such superimposed layer were 85 coated on to a grainy surface it would only come away with a "matt" or "ground glass" appearance, being a moulded reproduction of the grain of the paper.

The functions of the several component 90 layers are therefore all different. The paper temporarily reinforces and strengthens 95 the entire film. The celluloid forms the base that permanently supports the sensitized colloid with its image-series. The substratum effects a perfect and permanent union between the sensitized colored colloid 100 and the celluloid base. And the adhesive rubber or adhesive gelatine layer forms a temporary union between the paper reinforcement and the film itself.

What I claim as my invention and desire 105 to protect by Letters Patent is:—

1. A complete section film material of 110 double standard width and half standard thickness comprising three main layers, a transparent base support, a sensitive colloid with color incorporated therein in two longitudinal stripes of complementary colors and paper reinforcement with fine teeth or grain 115 on the surface in combination with layers of adhesive material.

2. A ready-colored, reinforced, double-width film-material having two side-by-side 120 parallel stripes of sensitized colloid with color incorporated therein permanently attached to a transparent base support of celluloid, the said film consisting of three layers, two of which, the transparent base support and colored colloid, being used permanently for building up a two-color film-print, and the third part, a strengthening reinforcing strip 125 of paper adapted to be used only temporarily and discarded at a convenient stage of the process.

- 4
3. A perforated cinematograph film-material comprising the combination of a transparent celluloid base of substantially half standard thickness and double standard width, a colored colloid layer in two longitudinal parallel stripes orange-red and blue-green and a removable reinforcing strip of paper provided with a fine toothed grained surface.
- 10 4. A ready-colored, reinforced, double-width film-material for the production of cinematograph two-color positive film-strip prints of standard width and thickness, but of the type built up from two thin films of only half the standard thickness which after printing are cemented together to form a single width film of standard thickness and comprising in its construction the following arrangement and combination of parts:—a
- 15 20 layer of paper having a multitudinous number of fine teeth upon one surface, which serves the double purpose of a casting support upon which the film is built up and formed during manufacture and also as a
- 25 30 temporary reinforcement detachable from the film at any convenient stage after printing, a temporary layer of adhesive material flowed into the hollows or spaces between the teeth of the paper layer, having a smooth upper surface; a layer of sensitized colloid containing coloring matter applied as two parallel stripes superimposed upon the tem-

porary adhesive layer, one of the stripes being colored orange-red and the other blue-green; a layer of transparent celluloid forming the film base-support, and a permanent layer of adhesive substratum material for effecting a permanent union between the layers of sensitized colloid containing coloring matter and the layer forming the film-support, the sensitized colloid layer being enclosed between the paper reinforcement and the transparent celluloid base, the double-width strip being intended to be longitudinally severed after printing to form two differently colored strips which are ultimately superimposed and cemented to form a single-width strip of two-color pictures.

5. A ready-colored, reinforced, double-width film-material as in claim 1 with its sensitized parallel strips colored red and blue respectively.

6. A ready-colored film strip as in claim 1, provided with perforations for accurately registering the prints upon the double-width strip, and for moving the film through projection apparatus when the two thin films have been cemented together to form a single film strip.

In testimony whereof I have hereunto set my hand.

JOHN EDWARD THORNTON.
